VARIABLE CAPACITY, REVERSIBLE FLOW HYDRAULIC ROTARY PUMP AND SYSTEM
Eugene J. Miller, 411 Oak Ave., McHenry, Ill.
Filed Nov. 18, 1959, Ser. No. 853,776
11 Claims. (Cl. 103—120)

The present invention relates to a variable capacity, reversible flow hydraulic rotary pump and system, and is particularly concerned with rotary pumps of the vane type in which the capacity of the pump and direction of its flow are adapted to be controlled without changing the direction of rotation of the shaft.

This application is a continuation-in-part of my prior application of the same title, Ser. No. 705,547, filed December 27, 1957, and now abandoned.

One of the objects of the invention is the provision of an improved rotary pump of the vane type which is adapted to produce a variable flow or capacity of oil under pressure from zero to maximum in forward or reverse flow direction, with the shaft rotating in the same direction, for use in a multiplicity of different applications in actuating hydraulic rams or hydraulic motors that require a constant capacity output at a variable speed input or which require variation of the output capacity of a hydraulic system.

An example of the use of such a hydraulic pump is in rotating concrete mixers by hydraulic actuating motors which are driven from the engine of an automotive vehicle, where the speed of rotation now drops off as the engine of the car slows down.

Another example of the use of such a hydraulic pump is for providing hydraulic fluid under pressure for controlling steering of the car, as the present hydraulic steering controls provide too much capacity at high speed and too little capacity at low speed.

Another example of the use of such a pump is in the hydraulic drive of any mechanism, including the driving wheels of an automotive vehicle.

Another object of the invention is the provision of an improved hydraulic pump control system including such a variable capacity pump and suitable speed controls for controlling the output of the pump and maintaining its flow and capacity constant at variable speeds or suitably varying its capacity and pressure at constant speeds of drive.

Another object of the invention is the provision of an improved variable capacity rotary pump of the vane type adapted to be used for compressing gases or liquids and a system for controlling the same which is simple in construction, capable of economical manufacture, constant, and positive in its performance, and adapted to be used for a long period of time without necessity for repair or replacement of its parts.

Another object of the invention is the provision of an improved variable capacity rotary pump of the vane type in which all of the connections for fluid or fluid conduits may be provided with rigid piping, as distinguished from the use of flexible conduits because the maintenance of fluid-tight joints is more easily and economically accomplished by using rigid piping.

Other objects and advantages of the invention will be apparent from the following description and the accompanying drawings, in which similar characters of reference indicate similar parts throughout the several views.

Referring to the drawings, of which there are four sheets,

FIG. 1 is a vertical axial sectional view, taken on the plane of the line 1—1, looking in the direction of the arrows, of FIG. 2;

FIG. 2 is a vertical sectional view, taken on the plane of the line 2—2 of FIG. 1, through the rotary pump;

2

FIG. 3 is a vertical elevational view in partial section on axial planes, showing the speed control for a hydraulic system, including the rotary pump of FIGS. 1 and 2;

FIG. 4 is a view similar to FIG. 3, showing the parts 5 of the control in the position which they assume upon zero flow of the pump;

FIG. 5 is a fragmentary view similar to FIGS. 3 and 4, showing the parts in the position for flow in the opposite direction;

FIG. 6 is a diagrammatic view, showing the hydraulic system and controls for operating a hydraulic motor at variable speeds and capacities or at constant speed and capacity with a variable input, with the parts in the position of no power output;

FIG. 7 is a similar view, with the parts in the position of rotation of the hydraulic motor output shaft in a counter-clockwise direction;

FIG. 8 is a view similar to FIG. 6, with the parts in the position for clockwise rotation of the output shaft;

FIG. 9 is a view similar to FIG. 8, with the parts in the position which they may assume under control of the governor when operating under the conditions of FIG. 8;

FIG. 10 is a top plan view of the elements of a hydraulic system of the type shown in FIGS. 3—9 with the 25 rotary pump of FIGS. 1 and 2;

FIG. 11 is a view in perspective of the movable compressor chamber used in the pump of FIGS. 1 and 2;

FIG. 12 is a view in perspective of the rotor of the rotary pump.

Referring to FIGS. 1 and 2, 20 indicates the housing of the hydraulic pump in its entirety, embodying the invention. The housing 20 may consist of two parts 18 and 19 forming a housing with a lower stable base 21, supporting an upper enlargement 22, which is provided with a substantially rectangular chamber 23.

The chamber 23 may have upper and lower plane inner walls 24 and 25; and its lateral plane walls 26 and 27 are provided by a pair of side plates 28 and 29. Thus the upper enlargement 22 of the pump housing may have a through rectangular aperture forming a chamber 23, with the side plates 28 and 29 closing the ends of this aperture.

The side plates 28 and 29 are adapted to be received in rabbeted recesses 30 and 31; and the side plates are provided with complementary rectangular formations 32 and 33 fitting in the rectangular recesses 30 and 31. The side plates are provided with laterally projecting flanges 34 and 35, having bolt apertures 36 for receiving the screw bolts 37 passing through the side plates and threaded bores 38 in the housing 20.

Each side plate 28 and 29 is provided with a through bore 39 and 40 for passing the rotor shaft 41; and the bores 39 and 40 have counterbores 42 and 43 for receiving the ball bearings 44, which in each case include an inner race 45, an outer race 46, and balls 47.

Each counterbore 42, 43 may have a snap ring for securing the outer races in the counterbore; and each counterbore may have an oil seal, comprising a leather seal 48, having a cylindrical flange and a radial flange 60 and a coil spring 49 holding the seal against the shaft; and a suitable closure plate 50 may be bolted to each hub 51 to enclose the oil seal.

The pump housing 20 is provided in its chamber 23 with a movable pump block 50, having a central portion which is rectangular in shape and provided with upper and lower plane walls 61, 62 and with the lateral plane walls 63, 64 so that the block 60 may be slidably mounted in the rectangular chamber 23.

The central enlargement of block 60 is shorter than chamber 23, thus providing a suitable clearance between block 60 and chamber 23, which permits the block 60

to move to right and left. Spaces 65 and 66 may be vented to air to permit block 60 to move.

The block 60 is provided at each of its ends with a cylindrical extension 67, 68, each of which may be integral with the block 60, and each of which is guided in a cylindrical bore 69, 70 communicating with the rectangular chamber 23. Each cylindrical extension 67, 68 has an integral tubular cylindrical extension 71, 72 which is slidably mounted in a cylindrical bore 73, 74; and each tubular extension has a tubular bore 75, 76, and is provided with a threaded end portion 77, 78 (FIG. 11) for attachment of rigid tubes adapted to carry oil under compression.

Each of the cylindrical bores 69 and 70 is long enough to receive the cylindrical extensions 67 and 68 of the block 60 with a clearance, leaving spaces 79 and 80 at the ends of the bores 69 and 70 for receiving oil under compression to actuate the block 60 from left to right and vice versa.

The oil inlet or outlet bores 81 and 82 extend into the housing 20 and communicate with the spaces 79 and 80 for admission or outlet of oil under pressure; and the bores 81, 82 have threaded counterbores 83, 84 for receiving the rigid oil conduits 85, 86.

The cylinders 67 and 68 have their cylindrical walls provided with peripheral grooves 87, 88 for providing space for the O rings 89, 90 of neoprene, which project from the grooves 87, 88 sufficiently to maintain oil-tight engagement with the cylindrical bores 69 and 70.

The cylindrical extensions 71 and 72, forming conduits 75 and 76, have partially circular grooves 91 and 92 for receiving O rings 93 and 94 of neoprene, which project from the grooves sufficiently to provide a liquid-tight contact with the counterbores 73, 74.

Block 60 is provided on each of its lateral surfaces with a partially circular groove containing a neoprene O ring 15, which itself is cylindrical in section and circular in elevation, sealing the block about the rotor in the cavity 61.

Thus the conduits connected at 83, 84 may be used to provide oil under pressure to the spaces 79 or 80 to move the block 60 back and forth, the purpose of which is to vary the capacity of flow and its direction of oil pumped from the compressor.

The tubular bores 75, 76 communicate with a cylindrical pumping chamber 100 in the block 60, extending from side to side and closed by the side plates 28 and 29. The chamber 100 may be cylindrical in shape so that the vanes move in a circle at all times and are urged outward by centrifugal force. The purpose of the cylindrical chamber shape is to reduce vane wear, or vane chatter caused by uneven circumference in vane pumps of the prior art.

Each of the lateral ends of pumping chamber 100 may be provided with oil relief grooves 101, 102 communicating with the bores 75, 76 to permit the oil to be driven out of the chamber 100 by the vanes 103, 104 carried by the rotor 105.

The rotor vanes 103 are preferably made of magnetizable metal, such as steel, having poles at the inner and outer ends of the blades, which are attracted outwardly to the walls of bore 100 and held in constant contact with the bore 100 by magnetic attraction. The rotor may be made of manganese or aluminum, which is not paramagnetic, and the side plates 28, 29 may be of bronze, thus eliminating magnetic attraction in other directions so that a constant seal is effected with the bore 100 without springs and without radial movement of the vanes.

The rotor 105 may form an integral part of the shaft 41 or be keyed thereto and is a cylindrical body provided with plane ends 106 and 107 and a cylindrical outer surface 108. The rotor 105 (FIG. 12) has a multiplicity of axially extending slots 109 (eight) for slidably receiving

the vanes 103, which are pressed outward by centrifugal force.

The slots 109 do not extend through the shaft 41 for the reason that there are differentials of oil pressure on opposite sides of the rotor.

Each vane 103 comprises a rectangular plate having plane surfaces on its opposite sides and ends and inner edge for slidably engaging in the grooves 109 with minimum leakage and for slidably engaging the end walls 26, 27 on the inside of the plates 28, 29.

Each vane has its outer edge 113 beveled to provide a line contact with the cylindrical wall of the pumping chamber 100; and the vanes 103 engage the walls of the chamber 100 at all times, the slots of the rotor sliding on the vanes.

Keeping the vanes at constant radial position also permits higher speed operation.

The rotor has neoprene plugs 104 in slots 110 to absorb shock and differentials of pressure, which cause heating of oil. A screw bolt may hold each plug in its slot.

The oil relief grooves 101, 102 allow oil to run ahead of the vanes; and grooves 101, 102 are absent at the seal areas 16, 17, which are a little wider than the vane space width.

The operation of the pump is as follows.

When the parts of the pump, and in particular the block 60, are in the position of FIG. 6, occupying a position half way between the lateral walls of the cylindrical chamber 100, no oil is pumped in either direction.

When the block 60 is in the position of FIG. 1, the pumping space 115, in advance of the rotor 105 and vane 103, rotating counterclockwise, is adapted to be diminished in size as the vane 103 progresses and to pump oil out of the conduit 75. The opposite space 116 increases in size, but pumps no oil because it is closed at the outlet conduit 76 and is not provided with the oil relief groove 101.

Oil is sucked in at the conduit 75, which is an inlet at this time; and oil is pumped out of the conduit 76.

When the parts are in the position of FIG. 8, the block 60 is at its left position; and the rotor 105, rotating in the same direction, pumps oil out of the conduit 75 and sucks oil in at the conduit 76.

At a position such as that in FIG. 9, where the block 60 is somewhat to the left of a central position, the oil flow out of the right hand conduit 75 is diminished in amount, depending on the position of the rotor in its chamber 100.

Thus the direction and capacity of the oil at the conduits 75 and 76 may be varied at will by varying the position of block 60, with the rotor 105 constantly rotating at the same speed in the same direction.

Referring to FIGS. 6-9, these are diagrams of a suitable control for providing the oil under pressure for the spaces 79 and 80 at the ends of the block 60 to move block 60 from left to right or vice versa or to hold it in the fixed central position.

In FIG. 6 the pump 20 is shown with the block 60 in the intermediate or central position where the rotor 105 pumps no oil because its pumping spaces 115, 116 are always of the same size.

In addition to the pump 20, the diagram shows conduit 76 communicating through conduit 127 with the inlet 120 of a hydraulic motor 121 of the gear type, having a pair of pumping gears 122, 123 meshing with each other and slidably rotating in the communicating partially cylindrical chambers 124, 125, so that the oil entering into tooth spaces is not carried around from inlet 126 to conduit 127.

Conduits 127 and 127a preferably lead to pressure equalizing chambers 128, which have oil 129 under compression by means of aerated neoprene balls 130 of foamed neoprene covered with a skin of neoprene, the oil being supplied through a valved conduit 132, to charge the system.

Conduits 85 and 86, extending from the spaces 79 and 80 at the ends of the block, communicate with the cylinders 134, 135, which are movably mounted on a frame 136 under control of the governor 137. The cylinders 134, 135 may be in the form of a ram provided with pistons 138, 139 controlled by piston rods 140, 141.

In FIG. 6 the pistons 138, 139 are in intermediate position to hold the block 60 in intermediate position for no flow and no pressure.

Referring to FIG. 3, this is an elevational view in partial section, showing the governor construction, in which the governor 137 and its associated parts are mounted upon a base 138. The base 138 has a column 139 at one end, supporting a fixed shaft 140, with its reduced end in a bore 141, where it is secured by a nut 142 on its threaded end 143, clamping the annular shoulder 144 against the end of hub 145.

The fixed shaft 140 has an elongated cylindrical body 146 rotatably supporting a driven pulley 147, having a V groove 148 for receiving a V belt; but the pulley 147 may be replaced by a gear in the case of a geardrive. The V pulley 147 may have an elongated hub 149 with a bearing bore 150 rotatably mounted on the shaft body 147 and confined against axial movement by the head 151.

The elongated hub 149 has a sliding governor collar 152 which is provided with a peripheral groove 153 for receiving the ends 154 of the governor control weight levers 155. These levers have enlarged masses 156 extending toward the V pulley 147 from the pivots 157 so that the masses are pivoted on the lugs 158 and tend to fly outward due to centrifugal force as the speed of rotation of the pulley increases.

The collar 152 has a groove for receiving a spline 159 on hub 149, engaging in groove 160 so that the collar 152 slides on hub 149, but rotates with it. Collar 152 supports a thrust ball bearing assembly 161, comprising an inner race 162 of angular shape with the ball groove 163; and a snap ring 164 in groove 165 holds the race 162 against annular shoulder 166.

A thrust ball bearing housing 167 has a cylindrical chamber 168 provided with a counterbore and annular shoulder 169, engaging the outer race 170, which in turn is angular in shape and provided with groove 171, and is held in place by a snap ring 172 in a suitable groove.

The balls 173 in the ball bearing assembly are subject to axial thrust and permit the thrust bearing 167 to stand still, while the collar 152 rotates in it and exerts axial thrust.

Thrust bearing housing 167 has a base plate 174, to which is bolted the base plate 175, supporting the ram cylinders 134 and 135. The ram cylinders have inlet-outlet conduits communicating with the cylinders at 176 and 177 and connected to conduits 85 and 86.

The ram pistons are shown at 138, 139 and the piston rods at 140, 141.

Centrifugal force acting on the governor weights 155, 156 is resisted by a coil spring 178 having one end hooked in an eye 179 carried by plate 175; and the other end is hooked in an aperture 180 carried by threaded rod 181. Threaded rod 181 is provided with a hand nut 182 and passes through an unthreaded bore 183 in column 184.

Rod 181 has a head 185 to be held while the nut 182 is tightened or loosened to adjust the tension on spring 178. The amount of tension of spring 178 determines the point at which the cylinders 131, 134 are moved toward the right for relieving the pressure on the oil in the cylinder space 186, which in FIG. 3 is controlling the position of block 60 by forcing oil under pressure through conduit 86 into space 80, urging the block 60 toward the right into the position of FIG. 1.

By relieving the pressure on oil in space 186 of ram cylinder 134 the block 60 is permitted to move slightly toward the left in FIG. 1, reducing the capacity output of the pump in response to the action of the governor

weights 155, which move the plates 174, 175 and the ram cylinders 134, 135.

The tension of spring 178 may be so regulated that a substantially constant output is maintained at the output conduit 75 of the pump 20.

In the embodiment of FIGS. 3-5 oil under pressure is maintained in only one of the spaces 79 or 80; and in FIG. 3 it is the space 80 which is subjected to oil under pressure by ram piston 138, the piston rod 140 of which is held in the position of FIG. 3 by engaging the end of a sliding rod 187 in tubular guide 188 carried by column 189.

Rod 187 is held in fixed position in FIG. 3 by control lever 190 pivoted at 191 on the lug 192, and having its handle 193 secured in a notch or groove 194 in the holding segment 195, which has additional laterally open notches 196 and 197. Holding segment 195 is mounted on column 189 and extends adjacent the path of handle lever 193, which is resilient; and the handle 193 must be bent laterally to get it out of one of the notches 194, 196, or 197.

In FIG. 3 the handle 193 is in the proper position for the pump to pump oil under pressure out of the conduit 76.

The other end of lever 190 has a pin and slot connection 198, 199 to a sliding rod 200 in tubular guide 201 carried by column 189.

Rod 200 may be positioned to engage the end of ram 141; but in FIG. 3 the rod 200 is free of the ram rod 141 by a clearance at 202 in the guide 201; and the cylinder 135 and piston 139 are exerting no pressure on the oil in space 203, which communicates by conduit 85 to the space 79 on the right of the block 60 in FIG. 1.

Thus the pressure in the space 79 at the right of the block 60 is relieved, and permitting the pressure in space 80 to hold the block 60 in the right hand position of FIG. 1.

Referring now to FIG. 4, the handle lever 193 is there in an intermediate position in the groove 196, with both the rods in the position of FIG. 4, where the rod 187 engages the end of piston rod 140 and rod 200 engages the end of piston rod 141.

The pistons 138 and 139 in FIG. 4 are in an intermediate position in which there is an equal amount of oil under pressure in space 186 and space 203 in the cylinders. The block 60 is then in the intermediate position of FIG. 6, where block 60 attains its own neutral position by so moving that it pumps no oil. The pump may run at 0 to 1000 r.p.m. without radial movement of vanes.

The connection of rod 187 to lever 190 is by a pin and slot 204, 205 because the sliding connection is necessary between the pivoted lever and the sliding rod.

Referring to FIG. 5, this is a fragmentary view, showing the ram pistons 138, 139 in the position of FIG. 8, where the rotor 105 engages the right side of the pumping chamber 106; and the conduit 75 becomes the outlet of the pump, with the conduit 76 acting as inlet.

The governor controls the amount of oil under pressure, which is forced into the space 79, urging the block 60 toward the left, and regulating the size of the compression spaces 115, 116.

In FIG. 5 the handle lever 190 has its handle located in notch 197 (not shown in FIG. 5); and the ram 134 would be inactive because its piston rod 140 would be out of engagement with rod 187.

FIG. 9 shows a position of the block 60 in which the block 60 has been permitted to move toward the right slightly from the position of FIG. 8 to reduce the output in conduit 76 responsive to the action of the governor.

In FIGS. 1-5 the governor pulley 147 is driven by a belt connected to the pulley of the output fluid motor at shaft 206 so that the governor speed of rotation depends on the speed of the output motor 121.

Referring to FIG. 10, this is a top plan view of one

form of hydraulic drive, including an electric motor 207 as a prime mover. Motor 207 may be replaced by an internal combustion engine, diesel engine, or any kind of motive power that is to drive the system and furnish hydraulic power, the capacity or pressure of which is to be varied.

This view shows a base 208 for mounting the prime mover 207, the pump 20, surge tank 128, fluid motor 121, and governor 137. The prime mover 207 drives the pump by means of pulley 209, V belt 210, and driven V pulley 211 on compressor shaft 41.

The pump 20 is connected by the conduits 85 and 86 to the rams 134, 135, which are governed by the governor 137. The pump 20 is connected by conduits 127 and 127a through the surge tank 128 to the fluid motor 121 at inlet-outlet 120, 126. Fluid motor 121 has a power outlet pulley 212 engaged by driven belt 213 for driving any kind of equipment, such as a power steering equipment, a concrete mixer, or the drive wheels of an automobile, or the oil may actuate rams of a dump truck.

The operation of the system is as follows: The rotor 105 of the pump 20 is held, except for rotation, in the same position in the pump 20 by the bearings 44; but the block 60 with its pumping chamber 100 may move relative to the rotor to the positions shown in FIGS. 1 or 6-9 to vary the direction or capacity of the fluid pumped by the pump.

The pump block 60 with its pumping chamber 100 is moved to the right or left by oil under pressure in the spaces 65 or 66; and this oil under pressure is supplied by the rams 134, 135, which provide oil through the conduits 85, 86 for moving the block 60 back and forth, causing it to pump, with its outlet at conduit 75 in FIG. 7, or to pump with its outlet at 76, in FIG. 8.

The rams 134, 135 and spaces 65, 66 and the connecting conduits have a suitable supply of oil in them, which is under pressure when the ram rods 140 or 141 are positioned to exert pressure.

When the ram rods 140, 141 are in the intermediate position of FIG. 4 or FIG. 6, the block 60 is free to move by internal pressure to the central position of FIG. 6; and the rotor 105 is centered in the pumping chamber 100, so that the pump pumps no oil in either direction.

When the block 60 is in the position of FIG. 8, the conduit 75 becomes the outlet conduit of the pump and the fluid motor 121 is driven in the clockwise direction. When the system is operating with either of its conduits 75 or 76 serving as outlet, the output or capacity of the pump is maintained constant by the governor 137 so that the prime mover 207 may operate at a variable speed, while the output of the fluid motor 121 is maintained constant by the governor 137.

It will thus be observed that I have invented an improved hydraulic pump which is adapted to have its pumping chamber moved relative to its rotor so that it may pump hydraulic fluid in either direction or may reduce its output to zero, while constantly rotating in the same direction, or its output may be varied in capacity while the pump shaft is constantly driven in the same direction at the same speed.

My pump and pump system may be employed on trucks to be driven by the truck engine to provide hydraulic power for actuating the rams, which control the tilting of the dump body, or for driving concrete mixers, or for driving the drive wheels of the vehicle or power steering.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as

new and desire to secure by Letters Patent of the United States, is:

1. A variable capacity pump of the vane type, comprising a supporting housing having a rectangular chamber provided with plane bottom surface, plane top surface, and plane side surfaces on side plates, a pump housing block shorter than said chamber, and having plane top, bottom, and side surfaces engaging the walls of said chamber for sliding movement of said block in said housing, said block having a cylindrical rotor chamber with its axis extending from side surface to side surface of said chamber in said block, said block having a rigid cylindrical block extension at each of its opposite ends, and each block extension being slidably mounted in a cylindrical extension chamber of said rectangular chamber, said block having a smaller cylindrical conduit extension extending from each block extension and slidably mounted in a cylindrical bore in each end of said supporting housing and defining liquid pressure chambers about each conduit extension at each end of said block, a rotor in said rotor chamber, and comprising a cylindrical member and a supporting shaft rotatably mounted in bearings carried by said side plates of said supporting housing, said shaft being centrally mounted in said side plates, and said rotor being cylindrical and smaller in diameter than the rotor chamber, but extending from end to end of the rotor chamber into engagement with the plane surfaces of said side plates, the said block having a range of movement in said supporting housing longer than needed to cause the rotor to engage the rotor chamber at either end of the block movement, said rotor chamber having diametrically oppositely located inlet-outlet ports, and a conduit extending from each of said ports in the block extensions and conduit extensions at each end of the block, a multiplicity of vanes located between the inlet-outlet ports on each side of the rotor, said vanes extending the full length of said rotor and slidably mounted in complementary radial slots in said rotor to be fully housed in the rotor slots with a clearance at the base of each vane when each vane is in the position to engage and pass one of said inlet-outlet ports, said vanes being mounted for free sliding movement, to be held radially outward in engagement with the cylindrical wall of the rotor chamber by centrifugal force, the vanes rotating in a constant radial position by engagement with the cylindrical walls of the rotor chamber and rotation of the vanes on the axis of the rotor chamber at all times to eliminate vane chatter, said rotor and the walls of the rotor chamber establishing a rotor seal at the leading edge of one inlet-outlet port and the vanes establishing a seal with the rotor chamber wall constantly with a compression chamber decreasing in size toward the rotor seal and a suction chamber increasing in size away from the rotor seal, the said rotor chamber having in its periphery tapered oil relief grooves tapering away from each port in opposite directions, and the grooves ending with their small ends at a point spaced from the inlet-outlet ports, which space is substantially equal to the spacing between two vanes, to provide a pumping zone only beyond the tapered ends of said grooves.
2. A variable capacity pump according to claim 1, in which the block extensions and conduit extensions have peripheral grooves in their cylindrical surfaces with resilient U rings substantially housed in, but projecting from, the grooves to establish a seal on both ends of the liquid pressure chambers, and the rotor has a groove defining a circle in each of the rotor ends, said latter groove containing a resilient O ring engaging the plane surfaces of the side walls of the rotor chamber.
3. A variable capacity pump according to claim 1, in which one liquid pressure chamber at one end of the block is filled with liquid under pressure and connected by a

conduit to a cylinder having a manually controlled piston for urging the block into rotor sealing position.

4. A variable capacity pump according to claim 3, and a centrifugal governor driven by the pump output and urging said latter cylinder in a direction to relieve pressure at the rotor seal upon increase of the output pressure.

5. A variable capacity pump according to claim 1, in which the rotor has peripheral recesses between each pair of vanes, the recesses containing a shock absorbing compressible solid, to absorb pressure impulses when a hydraulic fluid is being pumped.

6. A variable capacity pump of the vane type, comprising a supporting housing having a rectangular chamber provided with a plane bottom surface, plane top surface, and plane side surfaces on side plates, a pump housing block of paramagnetic material, shorter than said chamber, and having plane top, bottom, and side surfaces engaging the walls of said chamber for sliding movement of said block in said housing, said block having a cylindrical rotor chamber with its axis extending from side surface to side surface of said chamber in said block, a rotor in said rotor chamber, and comprising a cylindrical member and a supporting shaft rotatably mounted in bearings carried by the side plates of said supporting housing, said shaft being centrally mounted in said side plates, and said rotor being cylindrical and smaller in diameter than the rotor chamber, but extending from end to end of the rotor chamber into engagement with the plane surfaces of said side plates, said block being movable in said housing in either direction sufficiently to permit the cylindrical surface of said rotor to engage the cylindrical surface of the rotor chamber at either end of the range of movement of the block to effect a seal between the rotor and the rotor chamber at either end of said range of movement, said rotor chamber having diametrically oppositely located inlet-outlet ports at each end of the block where the rotor effects a seal adjacent either inlet-outlet port, a multiplicity of magnetized vanes slidably mounted in the rotor and extending radially thereof and located between the inlet-outlet ports on each side of the rotor, said vanes extending the full length of the rotor and being slidably mounted in complementary slots in said rotor to be fully housed in the rotor slots with a clearance at the base of each vane when any vane is in the position to engage and pass one of said inlet-outlet ports, said vanes being urged outward into engagement with the cylindrical wall of the rotor chamber by centrifugal force and magnetic attraction towards said cylindrical wall, and the vanes rotating with the rotor in constant engagement with the cylindrical walls of the rotor chamber, the vanes rotating on the axis of the rotor chamber at all times to eliminate vane chatter and vane movement except rotation, said rotor and the walls of the rotor chamber establishing a rotor seal at the leading edge of one inlet-outlet port, and the vanes establishing

a seal with the rotor chamber wall constantly, with a compression chamber decreasing in size toward the rotor seal and a suction chamber increasing in size away from the rotor seal, said rotor chamber having in its periphery tapered oil relief grooves tapering away from each port in opposite directions, and the grooves ending with their small ends at a point spaced from the inlet-outlet ports, which space is substantially equal to the spacing between two vanes, to provide a pumping zone beyond the tapered ends of said grooves.

7. A variable capacity pump according to claim 6, in which the rotor is provided with a V-shaped recess in its cylindrical surface between each pair of blades, the recess being filled with compressible resilient material for taking up the pulsations of pressure and producing an even flow.

8. A variable capacity pump according to claim 6, including means for urging said block in one direction inside said housing to establish a seal with said rotor and determine the direction and amount of volume of fluid delivered by said compressor.

9. A variable capacity pump according to claim 6, in which the compressor block may move to a central position with zero capacity output or to either end position, the rotor rotating in the same direction in all said positions.

10. A variable capacity pump according to claim 6, in which the block has a cylindrical extension sliding in a longer complementary cylindrical extension in said guiding chamber, and having an end surface subject to fluid pressure in a fluid chamber in said latter extension, to move the block to vary the relative position of rotor and rotor chamber to change the capacity of output.

11. A rotary vane pump according to claim 6, in which the cylindrical block extension and the rigid conduit extension have peripheral grooves containing O rings of neoprene to effect a fluid seal.
